SMOKING PIPE

George Lee Tanner, Dacula, Ga.

Application December 19, 1935, Serial No. 55,249

3 Claims. (Cl. 131—12)

This invention relates to a pipe filter, and it aims generally to provide a construction affording minimum opportunity for choking and which will serve to extract any liquid matter from the smoke.

5. It is further aimed to provide a tobacco or smoking pipe having a novel filter attachable in the stem thereof and readily removable for cleaning and repair.

It is still further aimed to provide such a construction equipped with a knob having a plurality, usually four, air passages and a core to which said passages conduct the smoke from the bowl, and which core has various smoke passages and liquid-extracting pits or wells.

15. The more specific objects and advantages will become apparent from a consideration of the description following taken in connection with the accompanying drawing illustrating an operative embodiment.

20. In said drawing:—

Figure 1 is a view of a smoking pipe constructed in accordance with the invention, and primarily being a substantially central longitudinal section;

25. Figure 2 is an enlarged longitudinal sectional view through the filter and adjacent portions of the pipe;

Figure 3 is a cross sectional view taken on the line 3—3 of Figure 2;

30. Figure 4 is a cross sectional view taken on the line 4—4 of Figure 2;

Figure 5 is a cross section taken on the line 5—5 of Figure 2;

Figure 6 is a cross section taken on the line 6—6 of Figure 2;

35. Figure 7 is a plan view of the core alone;

Figure 8 is a plan view of a modified form of core; and

Figure 9 is an end elevation of said modified form of core.

40. Referring specifically to the drawing, wherein like reference characters designate like or similar parts, 10 designates the bowl of a tobacco or equivalent pipe, having a hollow stem section 11 extending therefrom as usual, and the interior 45 of which stem is in communication with the bowl. An inwardly extending flange 12 extends partly across the said passage at the junction of the bowl and stem. A detachable mouth piece 13 is aligned with the stem and communicates with the bore thereof.

45. In accordance with my invention, a novel filter device to remove solid matter from the smoke, also to remove liquid matter from the smoke and to cool the smoke, is employed. This filter primarily consists of a tube 14 and a core 15 within

the tube. Said tube 14 removably and frictionally engages in the bore of the stem 11 and it has exterior screw threads on a portion 16 projecting outwardly beyond the stem and to which the mouth piece 13 is detachably screw threaded as shown. The core 15 extends removably and is frictionally held within the tube 14 and has an extension 17 projecting beyond the tube 14 and to which the mouth piece 13 is detachably screw threaded as at 18. Thus it will be seen that the 5 tube 14 serves to connect the stem and mouth piece together, and it will also be realized that upon moving the mouth piece 13 away from the stem 11, the tube 14 and core 15 will be retained with the mouth piece as a unit.

Said core 15 has a knob 19, provided with any desired number of longitudinal passages at 20, preferably four in number. The core also has a series of pits or wells 21 in the top thereof and a longitudinally extending groove or passage 22 10 in such top, intersected by said wells. Another passage or groove 23 extends centrally and longitudinally along the bottom of the core, terminating short of the front thereof, and arcuate spiral 15 passages 24 are provided about the core 15, communicating with the said passage 23 and with the wells 21 and accordingly with the groove or 20 passage 22.

Said passage 22 at the rear end communicates 30 with an arcuate passage 25, in turn communicating with the interior of the extension 17. Within said extension 17 a ball 26 is movably disposed, being retained by upsetting the end of the portion 17 as at 27, with intervening spaces 28 remaining, so that the ball 26 cannot completely cut 35 off the draft through the pipe, but will only prevent the passage of solid matter therethrough, that is, through the bore 29 of the mouth piece 13.

A knob 30 is carried at the forward end of the tube 14 and it has a plurality, preferably four, 40 longitudinally extending passages 31 through which the smoke is drawn from the bowl 10. The forward end of the knob 30 is generally spherical and the wall of flange 12 engaged therewith is preferably similarly shaped as at 32. It will be 45 noted that the knob 30 at the rear thereof has an enlargement 33 which is telescoped into the tube 14 and fastened therein by upsetting such tube as at 34.

As a result of the construction described the 50 smoke must take a tortuous course through the various passages insuring a cooling thereof before reaching the mouth piece 13. Solid matter will be removed or precipitated and cannot pass the ball 26 and enter the mouth. At the same time 55

the device will not become choked and any liquid matter will be deposited in the pits or wells 21 and hence not be conducted through the mouth piece.

5 The mouth piece may be readily removed at desired times for cleaning and the core may be readily detached from the mouth piece, and from the tube. In addition, it will be noted that the tube has openings 35 in radial alinement with 10 the wells or pits 21, so that when the mouth piece is detached, it may be inverted or shaken to enable the escape of collected matter from the wells.

Various changes may be resorted to within the spirit and scope of the invention. For instance, 15 as shown in Figures 8 and 9, the knob 30', identical with that at 30, is formed integral with the core 15', which is identical with that disclosed at 15, which integral part is associated with a tube 14 in the same manner as the knob 30 and core 20 15. If desired, a ball 26', functioning like that at 26, may be provided preferably slightly smaller in diameter than the bore of the extension 17, which ball is held in place by a removable pin 37, the removing of the pin permitting removal of 25 the ball 26' as an aid to the cleaning of the adjacent part of the core when necessary.

I claim as my invention:—

1. A chokeless pipe having a bowl, a stem communicating therewith and leading therefrom, a 30 mouth piece communicating with the stem, a tube within the bore of the stem and mouth piece connecting them together, a core within and removable with the tube, said core having a plurality of wells, a plurality of smoke passages 35 communicating with the bowl, wells and mouth piece, passages exteriorly surrounding the core and communicating with the wells at the top thereof, and a longitudinally extending passage intersecting all of the last-mentioned passages 40 and terminating short of the front of the core.

2. A chokeless pipe having a bowl, a stem communicating therewith and leading therefrom, a mouth piece communicating with the stem, a tube within the bore of the stem and mouth piece 45 connecting them together, a core within and re-

movable with the tube, said core having a plurality of wells, a plurality of smoke passages communicating with the bowl, wells and mouth piece, said passages including a longitudinally extending passage communicating with the wells at the tops thereof and with the bore of the mouth piece, spiral passages exteriorly surrounding the core and intersecting the wells at the tops thereof, a longitudinally extending passage communicating with all of the last-mentioned passages and terminating short of the front of the core, an extension at the forward end of the core disposed in the mouth piece, an obstruction carried by said extension, knob means adjacent the forward end of the tube having a plurality of longitudinally extending passages communicating with the bore of the tube, said knob having a part disposed in the tube, and said tube being upset to retain said knob.

3. A chokeless pipe having a bowl, a stem communicating therewith and leading therefrom, a mouth piece communicating with the stem, a tube within the bore of the stem and mouth piece connecting them together, a core within and removable with the tube, said core having a plurality of wells, a plurality of smoke passages communicating with the bowl, wells and mouth piece, said passages including a longitudinally extending passage communicating with the wells at the tops thereof and with the bore of the 30 mouth piece, spiral passages exteriorly surrounding the core and intersecting the tops of the wells, a longitudinally extending passage at the lower portion of the core communicating with all of the last-mentioned passages and terminating short of the front of the core, a knob at the forward end of the tube having a plurality of longitudinally extending passages communicating with the bore of the tube, said knob having a part disposed in the tube, said tube being upset to retain said 40 knob, a knob on the core in the rear of the first-mentioned knob having longitudinally extending passages on the exterior thereof, said knobs being integral with each other and with the core.

GEORGE LEE TANNER.
